1

This invention relates to apparatus driven by a fluid current such as the wind or water flowing in a materially level channel: said apparatus being of the kind in which a vane is mounted on a support constrained for movement transverse to the current, the vane being inclined to the current to derive transverse driving force from the latter and thereby drive itself and its support transversely to the current. A convenient arrangement is that in which the transverse movement is reciprocatory, in which case the apparatus includes means to reverse the inclination of the vane to the current upon the vane and its support arriving at each prescribed limit of their reciprocating movement; causing the current to drive the vane and its support alternately in opposite directions across the current. The vane support is connected to mechanism which makes use of its reciprocating movement.

When motion rather than power is the desired object as in the case of a flow meter, the vane may be of the flat plate type operating by reaction; but when power production is the object, the vane would in practice be an aerofoil which develops definite aerodynamic lift.

In such apparatus it is desirable for the inclination of the vane to be adjusted according to the ratio of the current velocity to the velocity of the vane across the current. In particular, it is desirable from the point of view of obtaining the maximum power from the current, that the true angle of incidence to the current should be maintained constant.

In the diagram, Figure VIII of the accompanying drawings, if the vector A represents the velocity and direction of the current, and B that of the vane across the current, the velocity and direction of the current relative to the vane is represented by C. If a is the optimum angle of incidence of the vane to the current, and b is the inclination of the vane to the horizon and it is desired to maintain a at more or less constant value, the angle b has to be adjusted approximately as the ratio A/B varies. It is a principal object of the invention to provide mechanism by which this adjustment is automatically achieved.

A further object of the invention is to provide mechanism including a servo-aerofoil adapted to make such automatic adjustment: to effect the periodic reversals of the inclination of the vane; and to govern the speed of the apparatus in high winds. The servo-aerofoil is also capable of statically counterbalancing the vane in so far as the latter is out of balance about its tilting axis.

According to the invention, apparatus as above described comprises a vane for exposure to the current, a support which constrains the vane for movement across the current, the vane being pivoted to the support to vary its inclination to the direction of the current, a servo-aerofoil pivotally

2 mounted for displacement by the current transversely to the latter, and motion-transmitting mechanism between the vane and the servo-aerofoil comprising a parallel-motion linkage of which one element is provided on the vane and the parallel element is linked to the servo-aerofoil, the mechanism acting to hold the vane to a substantially constant angle of incidence relatively to the current during movement of the vane across the current.

The servo-aerofoil is preferably of symmetrical profile possessing both high lift characteristics and high drag characteristics. Said servo-aerofoil is so mounted on a frame as to be displaced by the current across the latter, and is connected to the vane to tilt the latter from its position of zero inclination according to the displacement of the servo-aerofoil from a position of zero displacement.

20 The invention includes means whereby the arrival of the reciprocating vane and the vane support at the ends of their reciprocatory path causes the inclination of the servo-aerofoil to the current to be reversed, so that its displacement is reversed, causing in turn reversal of the inclination of the vane.

According further to the invention apparatus as described is governed against overspeeding by means causing diminution of the above mentioned 30 active torque, upon the current pressure becoming excessive. In one arrangement for this purpose the servo-aerofoil is capable of being displaced from its normal working position to a governing position by the drag exerted on it by 35 the current, and against the resistance of an initially loaded spring. When the servo-aerofoil is in such governing position, its capacity for setting up the active torque on the vane is diminished, as by lessening its own inclination to the 40 current.

An example of the invention constructed as a wind motor for directly driving a vertical reciprocating pump is shown in the accompanying drawings in which

45 Figure I shows the motor of the invention erected on its mast.

Figure II is a similar but more detailed view drawn to a larger scale.

Figure III is a plan of the servo-aerofoil detached from the motor framework.

Figure IV is an end view of Figure III.

Figure V is a plan view identical with Figure III but showing the servo-aerofoil swung back.

Figure VI is an end view of Figure V.

55 Figure VII is a much enlarged horizontal section through the servo-aerofoil.

Figure VIII is the diagram already referred to.

2 indicates the mast, stayed by guys 3, on which the motor is mounted at an elevation above the 60 ground. The pump rod 4 extends up through the

mast and from the open upper end thereof. At the top of the mast the head 5 is so mounted as to be freely rotatable about the axis of the mast. Said head 5 carries the framework 6, 6a of the motor. The motor comprises the rocking beam 7 pivoted in the bearings 8 on the frame part 6a to rock vertically about the horizontal axis 9. The bearings 8 are set back from the mast axis to constitute the portion 10 of the rocking beam as a lever that gives the necessary vertical reciprocation to the pump rod 4 as the beam 7 rocks. A weight 11 statically balances the aggregation of reciprocating parts, about the axis 9.

At the distant end of the rocking beam 7 is mounted the vane 12, having the function of driving the rocking beam up and down and so actuating the pump. Said vane 12 is an aerofoil positioned with its length transverse to the rocking beam 7 and the leading edge 13 of its section directed towards the mast so as to be driven by wind coming from the direction of the mast. The discs 14 at the ends of the aerofoil act as vanes to swing the motor around the mast as may be necessary to keep the aerofoil 12 trailing from the mast with its edge 13 presented to the wind. They also perform the function of diminishing power losses at the ends of the aerofoil 12. The section of the aerofoil is usually symmetrical about its chord and its profile is one having a high lift characteristic.

To the end of the beam 7 is rigidly fixed a transverse bearing sleeve 15 providing the horizontal pivot axis 16. Pivoted supported by said bearing sleeve 15 is the pressed metal bracket 17 to which the aerofoil 12 is rigidly attached, so that the aerofoil is capable of tilting about the axis 16. The centre of pressure 18 of the aerofoil is to the rear of said axis 16. An upward extension 19 of the bracket 17 forms a lever arm for controlling the degree and direction of the tilt of the aerofoil 12 about said axis 16.

Said arm 19 is connected by the rod 20 to a similar arm 21 of the bell crank 21, 22 which is mounted on the pin 23 of the bearing 8, and within a gapped portion 24 of the beam 7. Said pin 23 being concentric with the axis of the beam 7, the rocking of the latter has no effect on the transmission of angular movement from the bell crank 21, 22 to the aerofoil 12.

To the extent that the arm 21 remains stationary, the arms 19 and 21 together with the beam 7 and the rod 20, constitute a parallel linkage which maintains the aerofoil 12 at a constant inclination to the horizon independently of the rocking motion of the beam 7.

The rocking motion of the beam 7 is governed by the edge cam 25 fixed to and moving with said beam. The cam provides the two opposite curved edges 26, 27 the chords 28 of which are radial to the axis 9 about which the beam rocks; and the two opposite edges 29, 30 that are arcuate to said axis. The cam follower consists of the lever 31, 32 mounted on the frame 6 to oscillate about the horizontal axis 33. The upper arm 31 of said lever carries a pin or roller 34 that bears on the cam edges; and the edges 26, 27 are curved to the radius of 31. Said lever is pressed against said edges by means of the rod 35 attached to the lower arm 32 of the lever 31, 32. Said rod passes through an arm 36 that is fast with the beam 7 and rocks with the latter about the axis 9. On the rod 35 at opposite sides of the arm 36 the compression springs 37, 38 are confined by collars 39.

The angular separation of the chords 28, 29 determines the angular extent through which

the beam 7 rocks. Assuming that in Figure II the end of the rocking beam that carries the aerofoil 12 is descending and has reached the horizontal position, the arm 36 has moved correspondingly and has compressed spring 37 thereby pressing roller 34 against the cam edge 29. Said edge being concentric with the axis 9, the lever 31, 32 is held stationary. Continued descent of the beam brings the cam edge 26 to the level of the roller 34 which travels along said cam edge and thereby reverses the inclination of the lever 31, 32. By the means described hereafter, this latter action causes the aerofoil end of the beam 7 to reverse its motion and rise, whereupon the correspondingly reversed movement of arm 36, acting through spring 38, presses the roller 34 against cam edge 30 and causes the lever 31, 32 to be held stationary in its reversed position shown in Figure I, which shows the aerofoil end of the beam 7 rising and just about to reach the top position of its oscillation. Roller 34 then passes along the cam edge 27 and into position to regain contact with the cam edge 29; the lever 31, 32 correspondingly coming back to its Figure II position.

The angle of incidence of the aerofoil 12 is reversed upon the beam 7 reaching the above mentioned limits of its stroke, to cause said aerofoil to drive the beam alternately upward and downward. In the example under description, the several functions of thus periodically reversing the main aerofoil, maintaining the said aerofoil at the optimum angle of incidence to the wind, and governing the motor to protect it against high winds, are all made dependent on the servo-aerofoil 40.

The latter is preferably of symmetrical contour with high lift characteristics; being in these respects like the main aerofoil 12. In addition it has a high drag characteristic, for which purpose it is shown as formed with a projecting spherical enlargement 41 giving a drag value that is independent of the aspect of the servo-aerofoil to the current. The servo-aerofoil is mounted on a hollow shaft 42 projecting from a fork 43 which in turn is mounted, by means of trunnions 44, on the frame 6. This trunnion mounting gives the shaft 42 and the servo-aerofoil 40 carried by it, the capacity for vertical semaphore displacement about the horizontal axis 45.

This semaphore displacement of the shaft 42 is transmitted to the main aerofoil 12 and so as to adjust the tilt of the latter, through the arm 46 of the fork 43 and the rod 47 coupling said arm 46 to the bell crank element 22. Incidentally this coupling of the two aerofoils enables them to be statically balanced against one another with the result that their conjoint movements are uninfluenced by their weight.

The servo-aerofoil 40 is itself a motor deriving power from the wind to effect the cyclic tilting of the main aerofoil 12 and controlled by the cam 25 to move alternately up and down in synchronism with the rocking beam 7. Like the main aerofoil 12 it is tilted alternately up and down to cause its upward and downward displacement from a position of zero displacement corresponding to zero inclination of the aerofoil 12 to the current. Such tilting is effected by the rocking lever 31, 32 under the control of the cam 25. To said lever 31, 32 is fitted the universal joint 48 through which the angular motion of the lever 31, 32 is transmitted to a torsion rod 49, uninfluenced by movement of the shaft 42 about the

axis 45. Said torsion rod 49 is secured by its screw threaded end 50 and lock nut 51 to a head 52 mounted at the end 53 of the shaft 42 and rotatable relatively to said shaft. Said head 52 is attached by the pivot pin 54 to the internal framework 55 of the servo-aerofoil so as to tilt the latter about the axis 56 of the shaft 42 and the rod 49.

Another feature of the servo-aerofoil 40 is that it is capable of bodily movement in its own plane from a normal working position to any of a range of governing positions. This bodily movement is a swinging back movement about the axis 57 of the pivot pin 54, which axis is perpendicular to both the axes 45 and 56. To permit this movement, the end 58 of the servo-aerofoil through which the shaft 42 enters is formed with an elongated gap 59. Said end 58 is shaped in plan as an arc about the axis 57.

A rigid extension 60 of the fork 43 carries a roller 61 which extends into the gap 59, so as to be between the edges 62 of the latter and act as a stop limiting the extent of the tilt of the servo-aerofoil on either side of its position of zero tilt. Said gap 59 tapers in width in the direction from the leading edge 63 to the trailing edge 64 of the servo-aerofoil.

The tendency to swing bodily as described is set up by the drag of the wind on the servo-aerofoil and particularly on the spherical enlargement 41 which is positioned at the outer end of the servo-aerofoil to gain leverage. This tendency is yieldingly resisted by the spring 65 which is attached at one end to the head 52 and at the other end to the framework of the servo-aerofoil and is arranged to exert on the latter a moment about the axis 57 contrary to the moment exerted by the sphere 41, and normally holding the servo-aerofoil in the normal working position of Figure III; in which it is stabilized by its rib 66 pressing against the stop 67 extending from the head 52. In said normal position the centre of pressure 68 of the servo-aerofoil is, in plan, in the axial line 56 of the hollow shaft 42.

The three operations in which the servo-aerofoil takes part are performed as follows:

Periodical reversal of the main aerofoil.—Assume the motor to be in the Figure I position and the rocking beam 7, with the main aerofoil 12, to be rising. They are rising because the main aerofoil is inclined upward to the wind, and is subjected by the latter to positive lift.

The aerofoil 12 is retained in that tilted position by the servo-aerofoil which is also tilted up to the wind and derives lift force from the latter, which force it applies through the linkage 46, 47, 22, 21 and 20 to the arm 19.

Upon the cam edge 27 coming level with the pin 34 the lever 31, 32 rocks over, impelled by its spring 37 and thereby tilts the servo-aerofoil 40 downward about its axis 56 so that the servo-aerofoil derives downward lift from the wind. This lift force is transmitted through the aforesaid linkage to reverse the incidence of the main aerofoil 12 (Figure II) so that wind drives the main aerofoil downward. The elastic yielding of the torsion rod 49 permits the lever 31, 32 to snap over while the servo-aerofoil follows somewhat more slowly.

Setting of the vane to optimum angle of lift.—As already stated, the axis 16 about which the aerofoil 12 is mounted to tilt, is in front of the centre of pressure 18 of said aerofoil, so that the wind pressure tends always to tilt said aero-

foil 12 to its position of zero incidence. The same wind however acts on the servo-aerofoil 40 and tends to impart to the latter the semaphore displacement which, through the above mentioned linkage 46 to 19, increases the angle of incidence of the main aerofoil irrespective of whether the lift of the latter is upward or downward. The actual angle of incidence assumed by the main aerofoil 12 thus depends upon the balance of those two oppositely acting forces.

In making its reciprocating strokes, the main aerofoil 12 acquires velocity across the wind which diminishes its true angle of incidence to the wind; and is correspondingly less influenced by the direct tendency of the wind to tilt it towards zero incidence. This reduces the opposition of the main aerofoil to the tilting torque actively exerted on it by the servo-aerofoil 40. The latter shifts to a further position along its semaphore path and correspondingly tilts the main aerofoil to a greater angle of incidence, at which balance is again arrived at. The servo-aerofoil, having no material velocity across the wind, is not sensibly affected by variation of the A/B ratio.

Governing.—The last described action of the servo-aerofoil tends always to cause the main aerofoil to take the maximum of the power offered to it by the wind; and it is accordingly necessary to limit the power intake when that offered is excessive and would lead to unduly high rate of reciprocation of the rocking beam 7 and main aerofoil 12.

The spring 65 is so initially tensioned that it will not yield to the moment due to the wind pressure on the sphere 41, until said pressure becomes excessive. When that occurs the spring 65 yields and allows the servo-aerofoil to swing back towards the Figure V position.

One result is that the aerofoil profile virtually changes progressively to the form suggested in Figure VI, which has a lower lift characteristic and the aspect ratio is diminished as in Figure V. The active force exerted by the servo-aerofoil to tilt the main aerofoil is diminished, allowing the bias of the latter to diminish its angle of incidence, so that its speed is prevented from rising unduly.

Another result is that the centre of pressure 68 swings out of the axis 56 to a position behind said axis as indicated in Figure V. So long as 68 was aligned with axis 56, the wind pressure on the servo-aerofoil had no influence on the angle of incidence of the latter; but upon 68 coming behind 56, the servo-aerofoil assumes the biased condition of the main aerofoil 12 in which the wind tends to diminish its angle of incidence. This again causes the active torque on the main aerofoil 12 to be progressively diminished as the servo-aerofoil progressively swings back. The elasticity of the torsion rod 49 enables this to occur although lever 31, 32 remains stationary.

It is preferred to employ positive mechanical means for progressively limiting the angle of incidence of the servo-aerofoil. When the servo-aerofoil is in the normal working position of Figures III and IV, the roller 61 is within the widest portion of gap 59 and the servo-aerofoil is free to tilt either way from its zero position to the full extent required to give it the lift necessary to control the main aerofoil 12. As the servo-aerofoil progressively swings back to the position of Figures V and VI, the roller 61 comes into gradually narrower sections of the gap 59 so that the angle through which the servo-aerofoil can tilt is diminished more and more until the servo-

aerofoil is fixed in the position of zero incidence by the roller 61 coming into the small end 69 of the gap 59.

When the vane 12 is actuated by a water current, it is convenient to arrange it as well as the servo-aerofoil to reciprocate horizontally.

I claim:

1. Current driven apparatus comprising a vane for exposure to the current, a support which constrains the vane for movement across the current, the vane being pivoted to the support to allow it to vary its inclination to the direction of the current, a servo-aerofoil pivotally mounted for displacement by the current transversely to the latter, and motion-transmitting mechanism between the vane and the servo-aerofoil comprising a parallel-motion linkage of which one element is provided on the vane and the parallel element is linked to the servo-aerofoil, the mechanism acting to hold the vane to a substantially constant angle of incidence relatively to the current during movement of the vane across the current.

2. The apparatus claimed in claim 1, in which the movement of the vane support and the vane across the current is a reciprocating movement, and comprising means, rendered operative by approach of said parts to the ends of their reciprocatory path, to reverse the incidence of the servo-aerofoil to the current, whereby the transverse displacement of the servo-aerofoil is reversed and reverses the incidence of the vane to the current.

3. Current driven apparatus comprising an aerofoil support reciprocable across the current, an aerofoil of curved profile mounted on said support to share its reciprocating movement and pivoted on said support for adjustment of its inclination to the current, a servo-aerofoil exposed to the current and pivotally mounted for displacement transversely to the latter; and mechanism for transmitting movements of the servo-aerofoil to said aerofoil so that lift movement of the servo-aerofoil tends to increase the inclination of the aerofoil to the current and so that drag movement of said servo-aerofoil tends to decrease said angle, and means preventing drag movement at current velocities below a predetermined velocity.

4. Current driven apparatus comprising a vane for exposure to the current, a support which constrains the vane for movement across the current, the vane being pivoted to the support to vary its inclination to the direction of the current, and a servo-aerofoil pivotally mounted for displacement by the current transversely to the latter, and motion-transmitting mechanism connecting the servo-aerofoil and the vane whereby displacement movement of the aerofoil and tilting movement of the vane are positively dependent on one another.

5. Current driven apparatus comprising a vane for exposure to the current, a vane support movable about a fixed axis, which support constrains the vane for movement across the current, the vane being pivoted to the support to vary its inclination to the direction of the current, said vane being biassed towards the position of zero inclination to the direction of the current, and a servo-aerofoil pivotally mounted for displacement by the current transversely to the latter, the apparatus comprising mechanism to transmit displacement movement of the servo-aerofoil to the vane to tilt the latter about its axis, said mechanism comprising a parallel-motion linkage of which one element is provided on the vane and the parallel element is movable about said axis.

and of which the support is the third element, and a motion-transmitting link between the first named two elements the fourth; the mechanism acting to hold the vane to a substantially constant angle of incidence relatively to the current during movement of the vane across the current.

6. Current driven apparatus comprising a vane support reciprocable across the current, a vane mounted on said support to share its reciprocating movement and pivoted on said support for adjustment of its inclination to the current, a servo-aerofoil exposed to the current, motion-transmitting mechanism connecting said servo-aerofoil and said vane whereby movements of the servo-aerofoil are transmitted to said vane, and means, rendered operative by approach of said vane and vane support to the ends of their reciprocatory path, to reverse the incidence of the servo-aerofoil to the current, whereby the transverse displacement of the servo-aerofoil is reversed and reverses the incidence of the vane to the current, said reversing means comprising a cam and a cam follower only one of which reciprocates with the vane support, the cam providing for the follower a circuit with dimensions parallel to the reciprocatory path of the vane support and transverse thereto, the dimension parallel to the reciprocatory path controlling the extent of said path and the relative cam to follower movement in the other dimension governing similar movement of the follower to cause said reversal of the inclination of the servo-aerofoil.

7. Current driven apparatus comprising the combination of a frame, a beam pivoted on the frame to oscillate relatively thereto, a vane pivotally mounted on the beam to oscillate therewith and so as to be tiltable about an axis transverse to the length of the beam and thereby alter its inclination to the current, a servo-aerofoil pivotally mounted on the frame to be displaceable transversely to the current and also tiltable about an axis parallel with its length to alter its angle of incidence to the current, and mechanism for tilting the servo-aerofoil about said axis, said mechanism comprising a part movable bodily relatively to the frame and a part movable bodily with the aerofoil about the axis of said pivot, and a universal joint connecting said parts for motion transmission irrespective of displacement of the servo-aerofoil relatively to the frame, the apparatus also comprising motion transmission mechanism whereby the transverse displacement of the servo-aerofoil varies the inclination of the vane to the current.

8. Current driven apparatus comprising a vane support, a vane carried by said support for exposure to the current and movement across the latter, and pivoted to said support for adjustment of its inclination to the current direction and biassed towards the position of zero inclination to that direction, and means comprising an element directly movable by the current, and motion-transmitting mechanism connecting said element with said vane whereby the element exerts on the vane an active torque about the axis of the vane tending to increase its inclination to the direction of the current so that the actual inclination to that direction assumed by the vane at any instant is that due to the balance of the biassing force and the active torque acting on it at that instant, said apparatus also comprising means governing the apparatus against overspeeding, said means being arranged to cause diminution of the active torque when the speed limit is exceeded.

9. Current driven apparatus comprising a vane support, a vane carried by said support for exposure to the current and movement across the latter, and pivoted to said support for adjustment of its inclination to the current direction and biased towards the position of zero inclination to that direction, and means comprising an element directly movable by the current, and motion-transmitting mechanism connecting said element and said vane whereby said element exerts on the vane an active torque about the axis of the vane tending to increase its inclination to the direction of the current so that the actual inclination to that direction assumed by the vane at any instant is that due to the balance of the biassing force and the active torque acting on it at that instant, said element being a servo-aerofoil pivotally mounted for displacement by the current, and arranged so to be influenced by current pressure in excess of a predetermined value as to diminish the active torque it exerts on the vane.

10. Current driven apparatus comprising a vane support, a vane carried by said support for exposure to the current and movement across the latter, and pivoted to said support for adjustment of its inclination to the current direction and biased towards the position of zero inclination to that direction, and means comprising a servo-aerofoil pivotally mounted for displacement by the current transversely to the latter and for tilting movement to vary its inclination to the current and connected to said vane for exerting on the vane an active torque about the vane axis tending to increase the inclination of the vane to the direction of the current so that the actual inclination to that direction assumed by the vane at any instant is that due to the balance of the biassing force and the active torque acting on it at that instant, said aerofoil being also arranged to be so influenced by current drag in excess of a predetermined value as to diminish the active torque it exerts on the vane and being for this purpose mounted for bodily movement, by the drag of the current on it, from a normal working position to any of a range of governing positions, the arrangement comprising an initially loaded spring tending to retain the servo-aerofoil in a normal working position, the governing position taken up by the servo-aerofoil under the influence of excess drag being determined by the balance of the current drag on said servo-aerofoil and the resisting pressure of said spring.

11. Current driven apparatus comprising a vane support, a vane carried by said support for exposure to the current and movement across the latter and pivoted to said support for adjustment of its inclination to the current direction, and means tending to influence the inclination of said vane, said means comprising a servo-aerofoil pivotally mounted for displacement by the current transversely to the latter and for tilting movement to vary its inclination to the current, said servo-aerofoil being also mounted for bodily movement, by the drag of the current on it, from a normal working position to any of a range of governing positions, the apparatus comprising an initially loaded spring tending to retain the servo-aerofoil in a normal working position, the governing position taken up by the servo-aerofoil under the influence of excess drag being determined by

the balance of the current drag on said servo-aerofoil and the resisting pressure of said spring.

12. The apparatus claimed in claim 11, in which the servo-aerofoil is mounted to tilt about an axis parallel to its length, and including means rendered active by a movement of said servo-aerofoil towards a governing position, said means tending to tilt it about said axis in the direction to diminish its incidence to the current.

13. The apparatus claimed in claim 11, in which when the servo-aerofoil is in its normal working position, its centre of pressure is coincident with its tilting axis, and the bodily movement to a governing position displaces the centre of pressure, thereby causing the current drag to exert a moment on the servo-aerofoil tending to tilt the latter towards its position of zero incidence.

14. Current driven apparatus comprising the combination of a frame, a beam pivoted on the frame to oscillate relatively thereto, a vane pivotally mounted on the beam to oscillate therewith and so as to be tiltable about an axis transverse to the length of the beam and thereby alter its inclination to the current, a servo-aerofoil so pivotally mounted on the frame as to be displaceable transversely to the current and also tiltable about an axis parallel with its length to alter its angle of incidence to the current, means operated by the rocking of the beam, and arranged to reverse the incidence of the servo-aerofoil to the current and thereby to reverse the direction of the transverse displacement of the servo-aerofoil in synchronism with the oscillation of the beam, and motion-transmitting mechanism between the servo-aerofoil and the vane whereby the transverse displacement of the servo-aerofoil causes variation of the inclination of the vane to the current.

15. In a stationary apparatus suitable to be driven by a fluid current an arrangement comprising an aerofoil of curved profile, means allowing displacement of said aerofoil by the current transversely to the latter, means allowing tilting movement of said aerofoil to vary its angle of incidence relatively to the current, a servo-aerofoil pivotally mounted for displacement by the current, means connecting the aerofoil and the servo-aerofoil whereby movements of the servo-aerofoil are transmitted to the aerofoil, and further means allowing bodily movement of said servo-aerofoil, by the drag of the current on it, from the normal working position of the servo-aerofoil transverse to the current, in a direction substantially parallel to the direction of the current, and elastic means tending to maintain said aerofoil in said normal working position.
